DESIGN FOR A TOY CRIB

Richard H. Penndorf, Scarsdale, N. Y., assignor to Columbia Protekosit Co., Inc., Carlstadt, N. J., a corporation of New Jersey

Application May 25, 1945, Serial No. 119,732

Term of patent 7 years

(Cl. D34—15)

To all whom it may concern:

Be it known that I, Richard H. Penndorf, a citizen of the United States and resident of Scarsdale, in the county of Westchester and State of New York, have invented a new, original, and ornamental Design for a Toy Crib, of which the following is a specification, reference being had to the accompanying drawing, forming a part thereof, and of which Figure 1 is a side elevational view of a toy crib showing my new design; Fig. 2 is a fragmentary elevational view of the toy crib shown in Fig. 1 illustrating the outer face of the head; Fig. 3 is a fragmentary elevational view of the toy crib shown in Fig. 1 illustrating the outer face of the foot; Figs. 4 and 5 are fragmentary sectional views taken respectively on lines 4—4 and 5—5 of Fig. 2; and Fig. 6 is a sectional view taken on line 6—6 of Fig. 1.

I claim:

The ornamental design for a toy crib, substantially as shown.

RICHARD H. PENNDORF.
